UNITED STATES PATENT OFFICE.

HENRY T. SMITH, OF PROVIDENCE, RHODE ISLAND.

RADIATOR.

Specification of Letters Patent.

Patented Oct. 19, 1915.

1,157,188.

Application filed February 12, 1914. Serial No. 818,216.

To all whom it may concern:

Be it known that I, HENRY T. SMITH, a citizen of the United States, residing at Providence, in the county of Providence and State of Rhode Island, have invented new and useful Improvements in Radiators, of which the following is a specification.

This invention relates to radiators of the type commonly used on motor vehicles. Under the present usual method of manufacture, such radiators are built up with the casing and radiating element as one unit; sometimes this has been varied by making the casing or radiating element, or both, in sections, to facilitate assembling and repair work. Usually, however, when it is necessary to repair or clean the radiator it must be removed from the vehicle as one heavy unit, which is difficult to handle and impossible to clean out thoroughly.

The object of the present invention is to provide a unitary radiating element, of any preferred type, which may be readily inserted and removed from the casing as a unit, without disturbing the casing. This enables the radiating element to be easily cleaned or repaired and put back in the casing, or a new radiating element to be substituted.

Another advantage of my improved construction of radiator is that it enables radiating elements of different types of construction and suitable for motors of different horse-power, to be built up as units and kept in stock ready to be fitted into the casings of vehicles constructed according to the same system.

In the accompanying drawings: Figure 1 is a front elevation of a radiator constructed in accordance with this invention; Fig. 2 is a central vertical section of the same; Fig. 3 is a front elevation of a modified form of radiator; and Fig. 4 is a central vertical section through the same.

As shown in these views, the casing is a unitary structure comprising an upper water chamber 10 and a lower water chamber 11, connected by side walls 9. Chamber 10 has the usual inlet 8 and chamber 11 the outlet 7 for the circulating water. These chambers and side walls define the opening for the radiating element and, in the form of Figs. 1 and 2, the front edge of this opening has secured to it a flange 12, the projecting edge 13 of which is curved upwardly while the rear edge of said opening has a flange

14 secured to it, the rearwardly projecting edge 15 of which is curved inwardly as shown so that the opening in the back of the casing is made smaller than the opening in the front. The grooves of these flanges receive binding wires 16 and 18, hereinafter further described.

The radiating element consists of a honeycomb of tubes 17, which may be of any shape and of any suitable type of construction, built up into a unitary structure of a shape to fit the opening in the casing, and surrounded at its front end by a flange 19, which is curved to conform to the inside of the flange 12, 13. The rear edge of the radiating element has secured to it a flange 20, which is reversely curved to conform to the flange 14, 15, but does not extend as far at its free edge as the edge 15 of the flange 14, so that it can be inserted within said flange 14, 15. Preferably packing 21 is placed between the flanges of the casing and radiating element. After the two parts are thus assembled, clamping rings 16 and 18, provided with turn buckles 22 and 23, are placed in the grooves of the flanges of the casing and said rings are then contracted by means of the turn buckles and thus clamp the respective casing flanges firmly against the flanges of the radiating element, thus making a water-tight joint.

In the form of radiator shown in Figs. 3 and 4, the principle is exactly the same, but other means for securing the two parts together is illustrated, by way of example. Here the radiating element has secured to its front edge an angular flange 28, which is bolted to the casing, when the parts are assembled, by the bolts 32, packing being inserted if desired. The edge of the opening in the casing may be reinforced, but this is not shown.

The rear edge of the radiating element 27 has secured to it a flange 29, from which project stud-bolts 30, and the rear edge of the opening in the casing has secured to it an angular flange 26, provided with holes to receive said bolts, the nuts of which clamp the parts securely together.

It is immaterial to the spirit of my invention what particular means are used for securing the two unitary parts together, and I do not desire to be limited to those means shown, nor, as stated, does my invention depend upon the use of any particular type of radiating surface, the invention, as I regard

it, consisting in the provision of two unitary parts, the casing and the radiator proper, constructed to be readily assembled and disassembled, the radiating element being interchangeable with others of like shape and outside dimensions.

Having thus described my invention, what I claim as new is:—

10 A radiator of the class described, comprising a casing and a radiating member, the latter constructed to fit within the former, curved spring flanges on both the cas-

ing and said member adapted to fit into each other, and split wire rings laid around the flanges on the casing and provided with means to tighten them to bind the flanges together.

In testimony whereof I have hereunto set my hand in presence of two subscribing witnesses

HENRY T. SMITH.
